UNITED STATES PATENT OFFICE.

WILLIAM HURLEY SMITH, OF DEMING, NEW MEXICO.

AUTOMATIC LIQUID-ELEVATOR.

1,271,956.

Specification of Letters Patent. Patented July 9, 1918.

Application filed December 19, 1916. Serial No. 137,816.

To all whom it may concern:

Be it known that I, WILLIAM HURLEY SMITH, a citizen of the United States, residing at Deming, in the county of Luna 5 and State of New Mexico, have invented certain new and useful Improvements in Automatic Liquid-Elevators, of which the following is a specification.

My invention relates to devices for raising liquid from a lower level to a higher level, and particularly to means for lifting liquid by water power, this invention being an improvement on my prior application, Serial No. 523,859, filed October 21, 1909, 10 the object of the invention being to provide a construction whereby the water from a city water supply or like source of water under constant pressure may be used to elevate water or other liquid from a cistern, well, or other point to a higher level, a further object being to provide means whereby there may be a constant flow of water when a faucet or like outlet is opened.

My prior application above referred to, 25 included a pumping chamber connected at its upper end to a water reservoir and connected at its lower end to a water inlet pipe and a discharge pipe. Water being admitted to the pumping chamber and gradually rising 30 therein, forces a column of air from the upper portion of the pumping chamber into the reservoir, the air entering the reservoir in turn forcing out therein a certain amount of water to a discharge pipe. Thus the invention above referred to also included 35 means whereby when the water has risen to its full height in the pumping chamber, the inlet valve is closed and discharge valve automatically opened, the water passing out 40 of the pumping chamber to any suitable discharge and the air returned from the reservoir into the pumping chamber, thus permitting the reservoir to again fill with water.

My present invention includes in combination with the elements above mentioned, an intermediate compressed air tank into which air is forced from the pumping chamber, and from which compressed air is taken 50 to force out the water in the reservoir.

The invention also includes an air tank connected to the discharge pipe leading from the reservoir into which water may be forced from the reservoir when the faucet on 55 the discharge pipe is closed, thereby compressing the air therein, the air thus com-

pressed within the air chamber acting when the faucet is open to force water out of the discharge pipe, whether the reservoir is taking in water or discharging it.

The invention also includes means whereby the air within the air tank may be constantly replenished and kept under a constant pressure.

Further, the invention includes means whereby the compressed air forced into the water reservoir may be discharged into the water within the well or cistern, thereby acting to cool and purify the water in the cistern or well.

My invention is shown in the accompanying drawings wherein:

Figure 1 is a vertical section of my apparatus, the equalizing tanks being shown in elevation partly broken away.

Fig. 2 is an enlarged sectional view of the valve mechanism for the pumping chamber, the valves and valve stems being shown in elevation.

Corresponding and like parts are referred to in the following description and indicated in all the views of the accompanying drawings by the same reference characters.

Referring to these figures, 2 designates a well, cistern, or other chamber for the collection of water, and 3 designates a receptacle therein preferably located in the bottom of the well or cistern and forming a water reservoir or collecting chamber. This chamber 3 has an inlet opening in its lower end designated 4, whereby water may flow in from the well or cistern, this opening being provided with a check valve 5 which prevents the back flow of water. Extending from the lower end of the chamber or reservoir 3 is a discharge pipe 6 which extends to the locality to which water is to be raised or discharged. This pipe 6 is provided with a check valve 7 of any suitable construction, preventing the back flow of water in the pipe 6. The pipe 6 beyond the check valve 9 is connected by a branch 8 to an air tank 9 which is connected at its upper end to the water reservoir as hereinafter described.

Located preferably on a higher level than the chamber 3 and adjacent to the well or cistern, is a tank or chamber 10 which I shall hereafter denominate the pumping chamber. The function of this chamber 10 is to compress the air which is used for forcing out the water in the reservoir. The upper portion of this pumping chamber is

connected by a pipe 11 with a compressed air chamber 12, which at its bottom is connected by a pipe 13 to the upper end of the chamber 3.

5 An intake pipe 14 enters the lower end of the pumping chamber and a discharge pipe 15 extends therefrom. The intake pipe is to be connected to any suitable source of water supply under constant pressure, such as the 10 supply pipes of a city water system. The discharge pipe 15 may be connected to any suitable point of discharge, as a sewer.

The passage of water through the pipes 14 and 15 is controlled by valves 16 and 17 15 illustrated in detail in Fig. 2. The valve 17 upon an upward movement seats against a valve seat 18 so as to prevent the inlet of water into the pumping chamber, while the valve 16 seats against a valve seat 19 upon a 20 downward movement of the valve. Thus the valve 17 will be held to its seat by pressure in the pipe 14, while the valve 16 will be held to its seat by pressure in the pumping chamber 10. These valves are preferably 25 carried upon a yoke 20 which forms the lower end of a tubular rod 21 mounted upon any suitable guide. The tubular rod 21 is raised or lowered by means of a float 22 which is freely movable upon the tubular 30 rod. The rod 21 is provided with spaced stops along its length, designated 23 and 24, with which the float engages at the extremity of its upward or downward movement. Preferably, the rod 21 is guided in its vertical 35 movement by means of a rod 25 attached to the upper end of the tank 10 and extending down loosely into the tubular rod 21.

It will be seen that by this construction the rod 21 and the valves attached thereto 40 are moved in one direction when the float arrives at the upper end of the tank, and in the other direction when the float sinks toward the lower end of the tank. A downward movement of the rod 21 and the yoke 45 20 closes the valve 16 and opens the valve 17, while an upward movement of the rod 21 and the yoke 20 closes the valve 17 and opens the valve 16.

In Fig. 2 the outlet valve 16 is shown as 50 being seated on the seat 19 and closing the discharge opening, while the valve 17 is shifted from its seat and the inlet opening is opened. Water is now entering from the pipe 14 and therefore the full force of the 55 city water is in the tank and of course on the valve 16, holding it against the seat 19 with the full city water pressure, say 30 lbs. to the square inch. When the float 22 reaches the shoulder 23, it must lift with 60 sufficient force to overcome the city water pressure on the valve 16. As soon as the float lifts the rod 21 and the yoke, the pressure of the water in the pipe 14 acts against the valve 17 to close it. The valves are thus

shifted very quickly by the force of the 65 water pressure on the valve 17. Pressure in the pumping chamber is now relieved and the contents of the pumping chamber pass out through the discharge pipe 15. The 70 valve 17 is now held to its seat against by the full pressure of the city water under it in the pipe 14. The pressure against this valve holding it to its seat is exactly the same per inch as the pressure on the other valve when it is on its seat. To reverse the 75 valves, the float must each time overcome the pressure of the city water on the valve which is seated. As soon as this has been overcome by the float, the pressure of the water will act to quickly shift the valves. 80

Extending into the upper portion of the pumping chamber 10 is the air inlet pipe 26 provided with a check valve 27 permitting air to enter the chamber 10 when the pressure therein is reduced but preventing the 85 outward passage of air. The pipe 11 which connects the pumping chamber with the compressed air tank 12 is also provided with a check valve 27^a which permits the passage 90 of air from the tank 10 into the compressed air tank 12 but prevents the return of air.

The water reservoir 3 is provided with a like valve arrangement to that previously described, this arrangement, however, permitting in one position the entrance of air 95 from the compressed air tank 12 into the reservoir 3, and in its other position permitting the outlet of air from the tank 3 into the water of the well or cistern. To this end the pipe 13 opens into a valve casing 28 which has a seat 29 at its lower end. The valve chamber 30 which is preferably formed in conjunction with the valve chamber 28, has a valve seat 31 at its upper end, the chamber 30 opening into the well or cistern. The valves 32 and 33 are mounted on a yoke 34, the valve stems being of unequal length, and this yoke 34 is in turn attached to a tubular rod 35 moving freely upon a guide rod 36 in precisely the same manner as the 105 tubular rod 21 moves upon the guide rod 25. The tubular rod 35 is provided with stop collars 37, 37^a, spaced from each other with which the float 38 engages at opposite ends of its travel. 110

The operation of so much of my invention as I have described is as follows: As the water rises in the pumping chamber 10, it will force air into the tank 12. When the water falls in the pumping chamber 10, air will be drawn in through the pipe 26. The pumping chamber 10, therefore, forces air into the compressed air tank 12 until the air in the compressed air tank 12 is compressed 120 to the density of the air in the pumping chamber. When the air in the compressed air tank 12 is under the same pressure as the pressure in the pipe 14, then the pumping 125

tank will rest as the air in the upper portion of the pumping chamber cannot pass off into the compressed air tank 12 and the water in the pumping chamber cannot rise.

- 5 The compressed air tank 12 is thus kept filled at all times with compressed air which is ready for instant use in the reservoir tank 3. As before stated, the double valve 32 and 33 in the reservoir tank is the same as 10 the double valve in the pumping chamber and the arrangement for its actuation is the same. When the float 38 in the reservoir tank comes in contact with the shoulder 37^a and reverses the valves, the valve 32 seats 15 at 29 and thus prevents more air from entering from tank 12 through pipe 13. At the same time the valve 31 is open and permits the air in reservoir 3 to escape into the water. The reservoir 3 now fills with water 20 from the well through the passage 4. The float 38 rises with the water and when it comes in contact with the shoulder 37, the valves 32 and 33 are again reversed and the valve 33 seats at 31 and the valve 32 is 25 opened, permitting compressed air to again enter from the compressed air tank 12 through the pipe 13.

Were it not for the air chamber 9, the supply of water through the discharge pipe 6 30 would be intermittent. The chamber 9, however, provides a chamber where a certain amount of air is kept under compression and so connected to the discharge pipe 6, that the air pressure within the chamber 9 will act to 35 force out the water in the chamber 9 and thus cause a constant supply in the discharge pipe, even though at the time the water is being drawn from the discharge pipe, the reservoir 3 is taking in water and 40 is not yet ready to discharge water. If there was no chamber 9, it will be obvious that were the reservoir 3 taking in water, there would be no pressure in the discharge pipe 6 and that the consumer would have to 45 wait until the reservoir 3 had fully filled before he could get any water from the pipe 6. By using the air chamber 9, if the faucet 42 is closed at the end of the pipe 6, then the compressed air in the reservoir 3 50 will force water into the air chamber 9 and the water will rise therein and compress the air in the upper portion of the chamber. This compressed air will act to keep a steady flow through the discharge pipe, even though 55 the reservoir 3 is filling.

In order that a constant level of water may be maintained within the air chamber 9 and a constant pressure of air maintained therein, I connect the chamber 9 to the reservoir by means of a pipe 39 provided with a check valve 40. A spring 41 acts to hold the valve to its seat. This check valve permits air to pass from the reservoir 3 into the air chamber 9 but prevents its returning from the air chamber into the reservoir. 60

Starting with the system when first installed, both the reservoir and the air chamber will be full of water which has entered through the opening 4 into the reservoir and passed thence through the pipe 6 into the air chamber 9, the faucet 42 being closed, and there being at this time no air pressure in the reservoir 3. When the pumping chamber 10 is put in operation, the compressed air tank 12 will fill and the pressure 70 will be transmitted to the water in the reservoir 3. As water is drawn through the pipe 6 by the opening of the faucet 42 air will enter the reservoir 3 from the compressed air tank 12, and this air will pass 75 through the pipe 39 into the air chamber 9. As water seeks a level under uniform pressure, the water in both the reservoir and air chamber will remain at a like level as the water is drawn from pipe 6 and the 80 level is lowered. When the float in reservoir 3 reaches the shoulder 37^a and reverses the valves, the water in the two tanks will be at the level *a—a*. Immediately upon a reversal of the valves 32 and 33, the air will 85 pass out of the reservoir into the well or cistern and the reservoir will fill with water, but the water in the air chamber 9 will remain at *a—a*, the air in the air chamber being under full pressure. If no water is 90 drawn off through the pipes 6, while the reservoir 3 is filling, no change will take place in the level of the water in the air tank 9 and the water in the reservoir will again be under pressure when the reservoir has 95 filled and the valves are reversed.

As the reservoir now has the full air pressure plus the weight of the water therein, water will pass out of the reservoir when the faucet in pipe 6 is open and no air will 100 pass through the pipe 39 into the air chamber 9 until the water in the reservoir is again at the level *a—a*. If, however, water is drawn through the pipe 6 while the reservoir is filling, the compressed air in the 105 air chamber 9 will force the water from the air chamber 9 up through the pipe 6. When pressure is again resumed in the reservoir 3, the water level in the air chamber 9 has sunk to the level *c—c*. As the air in the 110 air chamber is not now under full pressure, and as the water in the reservoir will be forced out through the pipe 6, not only by the full pressure of the air but also by the weight of the water, water will pass from 115 the reservoir 3 through the pipe 6 into the air chamber 9 and will so continue until the air pressure is equal in the two tanks. Thus water will enter the air chamber 9 from reservoir 3 until the level in the tank 9 is 120 again at point *a—a*. Theoretically, no air will pass through the pipe 39 into the air chamber 9 while the air chamber is filling from the reservoir because the pressure of 125 the air in the reservoir, plus the weight of 130

the water therein, is greater than the air pressure alone in the air chamber 9. Hence water will enter the air chamber 9 from the reservoir 3 and no air would pass through 5 the connection 39.

In order to prevent puffs of air from entering the air chamber 9 through the connection 39 when the valves are reversed, a spring is used behind the valve 40, the spring 10 being strong enough to resist the pressure of the air when it first enters the reservoir but not strong enough to resist the full city water pressure.

In practice, this construction will maintain the same amount of air in the air chamber 9 and each time after use the water will return to the level $a-a$. If the water rises above the level $a-a$, then some of the air is exhausted from the air chamber 9, and when 20 the water in the reservoir 3 reaches the level of the water in the air chamber, air will pass through the connection 39 into the air chamber and the columns of water in the air chamber and reservoir will go down together until 25 the valves reverse and the water level in the air chamber is again at $a-a$. In this way and by this very simple arrangement, a constant supply of air is maintained in the air chamber without attention.

30 It is to be noted that the shoulder 37^a should be spaced from the shoulder 37 at such distance that when the float reverses the valves, the water in the reservoir will be at the level $a-a$, for the reason that if the 35 shoulder 37^a is too far down within the tank and too near to the bottom thereof, there will not be enough water left in the air chamber 9 to give a full supply until the reservoir 3 has again filled. There must be enough 40 water left in the air chamber 9 to last until the valves in the reservoir 3 have reversed and air pressure is again on in the reservoir 3. It will be seen that the construction I have just described compensates for the absorption of air by the water in the air chamber 9 and automatically replenishes the air therein and keeps it at a certain definite pressure.

In the construction which I have herewith 50 illustrated, the heating of the air under compression and the cooling of the air under expansion must be taken into account as the compressed air from the reservoir 3 is discharged into the water in the well or cistern. 55 By the construction illustrated I discharge cool air into the cistern through the outlet valve chamber 30, thus cooling the water in the cistern or well. The operation of my invention in this regard is as follows.

60 Beginning with the pumping chamber 10, the air compressed in this tank is heated by said compression. Much of this heat is radiated from the pumping chamber before the air passes into the compressed air tank 65 12. As the tank 12 is constantly charged

with compressed air and as the air remains in that tank for a relatively long time, the air will be about the temperature of the surrounding atmosphere when it passes from the tank 12 into the reservoir 3. Only a 70 relatively small amount of air enters the reservoir 3 at the moment when the valves are reversed, the reservoir at that time being filled with water. The air, therefore, which is forced into the reservoir 3 has 75 plenty of time in which to radiate the heat caused by the compression it receives before it enters the reservoir 3. When the reservoir 3 is emptied of water, it is full of compressed air. When the valves are reversed to close 80 the inlet pipe from the compressed air tank 12 and open the outlet to the cistern or well, this compressed air escapes into the water and of course expands to its normal density. The cooling by expansion exactly equals the 85 heating by compression. The liberated air, therefore, is quite cold as it expands through the water and not only tends to purify the water in the well or cistern, but will keep 90 it cool. This water is therefore at all times 95 pure and cold and no ice is needed to cool it. Water in the city water mains is warm in the summer months, and even if the water is pure, it is unpleasant to drink. By using my apparatus, water is always drawn 95 from the bottom of the well or cistern and it is always pure and cold. In the actual practice of my invention a commingler will probably be attached at the discharge opening in the valve chamber 30, but as these 100 comminglers are well known, it is not believed that it is necessary to describe them.

What I claim is:

1. An apparatus for elevating liquids, including a water reservoir having a water inlet, a discharge pipe and an air outlet, a compressed air storage tank connected to the reservoir, means for intermittently compressing air in said tank, means for alternately establishing connection between the compressed air tank and the water reservoir and simultaneously closing the air outlet and disestablishing said connection and simultaneously opening the air outlet, an air chamber connected at its lower end to the discharge pipe and connected at its upper end to the upper end of the water reservoir, a check valve in said connection, and means located in the discharge pipe beyond the air chamber for controlling the passage 110 of liquid through the discharge pipe.

2. An apparatus for elevating liquids, including a reservoir having a water inlet, an air inlet and an air outlet, a discharge pipe extending from the reservoir and provided 125 with a faucet, an air chamber connected to said discharge pipe, a check valve located in the discharge pipe between the air chamber and the reservoir, a connection from the upper end of the air chamber to the upper 130

- end of the reservoir, a check valve in said connection, means for compressing air, a connection from the air compressing means to an air inlet of the reservoir, a valve for controlling the inlet of air, a valve controlling the outlet of air from the reservoir, said valves operating alternately, a tubular rod operatively connected to the valves to alternately actuate the same and having opposed shoulders, and a float loosely surrounding the rod and located in the reservoir, said float being adapted to actuate the rod to alternately open and close said valves when the float reaches the extremities of its movement.
3. An apparatus for elevating liquids, including a water reservoir having a compressed air inlet and provided with an air outlet, said reservoir having a water inlet, a discharge pipe leading from the water reservoir, alternately operating valves for alternately closing the air inlet and simultaneously opening the air outlet or opening said air inlet and simultaneously closing the air outlet, a float in the reservoir for operating said valves, an air chamber connected at its bottom to the discharge pipe, a connection between the upper end of said air chamber and the upper end of the water reservoir, a check valve in said connection, and a check valve located in the discharge pipe between the water reservoir and the air chamber.
4. An apparatus for elevating liquids, including a reservoir having a water inlet and a discharge pipe, an air inlet and an air outlet, means for intermittently forcing compressed air into the upper portion of said reservoir, means in the reservoir for alternately opening the air inlet and closing the air outlet when the air is being forced into the reservoir and for opening the air outlet and closing the air inlet to permit the discharge of compressed air, a float located in the reservoir for controlling said means and actuated by the rise or fall of water in the reservoir, an air chamber connected to the discharge pipe, a check valve in the discharge pipe between the air chamber and the reservoir, and means for admitting compressed air into the upper portion of the air chamber when the compression of the air therein is reduced below a predetermined point.
5. An apparatus for elevating liquids, including a reservoir having a water inlet and a discharge pipe, a compressed air inlet and an air outlet, means for alternately opening the compressed air inlet and simultaneously closing the air outlet while the compressed air is being forced into the reservoir and opening the air outlet and closing the air inlet to permit a discharge of compressed air while the reservoir is filling, a float located in the reservoir for controlling said means and actuated by the rise or fall of water in the reservoir, an air chamber connected to the discharge pipe, a check valve in the discharge pipe between the air chamber and the reservoir, and means for admitting compressed air into the upper portion of the air chamber when the compression of the air therein is reduced below a predetermined point.
6. The combination with a well, of a water reservoir located at the bottom of the well and having a water inlet in its bottom and an air inlet and an air outlet in its upper end, said air inlet being connected to a source of air under pressure, a discharge pipe extending from the bottom of the water reservoir to a desired point and having a valve for controlling the passage of water therethrough, means located within the reservoir for alternately opening the compressed air inlet and closing the air outlet while the air is being forced into the reservoir and opening said air outlet and simultaneously closing the air inlet to permit the discharge of compressed air while the reservoir is filling, a float located in the reservoir for controlling said means, said float being actuated by the rise or fall of water in the reservoir, an air chamber connected to the discharge pipe, a check valve in the discharge pipe between the air chamber and the reservoir, and means for admitting compressed air from the upper portion of the reservoir into the upper portion of the air chamber when the pressure of the air in the air chamber falls below a predetermined point.
7. An apparatus for elevating liquids including a water reservoir having a water inlet, a discharge pipe and an air outlet, a compressed air tank connected to the water reservoir, means for intermittently compressing air in said tank, means for alternately establishing communication between the compressed air tank and the reservoir and simultaneously closing the air outlet from the reservoir and disestablishing said connection between the compressed air tank and the reservoir and simultaneously opening the air outlet, and an air chamber opening into the discharge pipe and connected at a point remote from its outlet with the reservoir to receive the air pressure of the compressed air tank from the reservoir upon the establishing of the connection between the compressed air tank and the reservoir.
8. An apparatus for elevating liquids including a water reservoir having a water inlet, a discharge pipe and an air outlet, means for alternately admitting compressed air into said reservoir and forcing the air out therefrom through said discharge pipe and for discharging the air and allowing

water to enter said reservoir, an air chamber connected to the discharge pipe and also connected at a point remote from its outlet with the reservoir to receive the pressure of air admitted to the reservoir, the discharge pipe providing communication between the outlet of the air chamber and the reservoir,

a check valve controlling back flow from the air chamber to the reservoir through the discharge pipe, and means located beyond 10 the air chamber for controlling the flow of water through the discharge pipe.

In testimony whereof I affix my signature.
WILLIAM HURLEY SMITH. [L.S.]
